CLAIM

The ornamental design for a container cover, as shown and described.

DESCRIPTION

FIG. 1 is front, top, and left side perspective view of a container cover according to the new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top view thereof;

FIG. 7 is a bottom view thereof; and,

FIG. 8 is a back, bottom and right side perspective view thereof.

The broken lines in the drawings illustrate portions of the container cover that form no part of the claimed design.

1 Claim, 8 Drawing Sheets
